RACING TRACKWAY GAME BOARD

Leonard H. McRoskey and John W. McRoskey, Los Angeles, Calif., assignors to Republic Tool & Manufacturing Corporation, a corporation of California

Filed Oct. 28, 1966, Ser. No. 4,460

Term of patent 14 years

(Cl. D34—5)

FIG. 1 is a top plan view of a racing trackway board showing our new design;

FIG. 2 is a front side elevation of the view in FIG. 1, the back side being a mirror image thereof;

FIG. 3 is an elevational view of the left end of the view in FIG. 1, the right end being a mirror view thereof; and

FIG. 4 is an enlarged sectional view taken substantially on line 4—4 of FIG. 1.

We claim:

The ornamental design for a racing trackway game board, as shown and described.
